(57) **CLAIM**

The ornamental design for display screen or portion thereof with icon, as shown and described.

DESCRIPTION

The FIGURE is a front view of a display screen or portion thereof with icon, showing our new design.

The circular solid line surrounding the heart icon represents an edge of the display screen. The broken lines in the Figure depict portions of the article on which the display screen is embodied, as well as portions of the display screen or portion thereof with icon. These broken lines form no part of the claimed design.
